US00D726198S

(12) **United States Design Patent**
Kim et al.

(10) **Patent No.:** **US D726,198 S**
(45) **Date of Patent:** ** Apr. 7, 2015

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Jaein Kim**, Goyang-si (KR); **Ho Kim**,
Seoul (KR); **Jinah Park**, Seoul (KR)

(73) Assignee: **Samsung Electronics Co., Ltd.**,
Suwon-si (KR)

(**) Term: **14 Years**

(21) Appl. No.: **29/490,392**

(22) Filed: **May 9, 2014**

Related U.S. Application Data

(63) Continuation of application No. 29/456,204, filed on
May 29, 2013.

(30) **Foreign Application Priority Data**

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design. The broken lines illustrating portions of the display screen or portion thereof with graphical user interface form no part of the claimed design.

1 Claim, 1 Drawing Sheet
